UNITED STATES PATENT OFFICE.

LEWIS PETER BOURGEOIS, JR., OF GRAMERCY, LOUISIANA.

HOOK-AND-EYE SAFETY-LOCK.

1,325,433.

Specification of Letters Patent.

Patented Dec. 16, 1919.

Application filed October 2, 1919. Serial No. 327,928.

To all whom it may concern:

Be it known that I, LEWIS PETER BOURGEOIS, Jr., a citizen of the United States, residing at Gramercy, in the Parish of St. James and State of Louisiana, have invented certain new and useful Improvements in Hook-and-Eye Safety-Locks; and I do hereby declare the following to be a full, clear, and exact description of the invention, such as will enable others skilled in the art to which it appertains to make and use the same.

The present invention relates to improvements in hook and eye safety locks, and has for an object to provide an improved device for holding the hook in the eye until such device is released to permit disengagement of the hook.

It is a further object of the present invention to provide a device for the above described purpose which will be simple and cheap in construction, capable of being readily applied where desired, and easy in operation.

In the accompanying drawings forming a part of this application, and in which similar reference symbols indicate corresponding parts in the several views:

Figure 1 is a perspective view of an improved hook and eye safety lock constructed in accordance with the present invention and shown applied to a door shown in fragmentary section.

Fig. 2 is a fragmentary elevational view of the improved device shown as applied to the door shown in section and broken away; and

Fig. 3 is a plan view of the improved device.

Referring more particularly to the drawings, 1 designates a door adapted to close in a door jamb 2, and 3 represents a hook having an eye 4 at its opposite end mounted in a screw eye 5 which is carried by the door jamb 2. The hook 3 is adapted to engage through an eye 6 carried by the door 1 so that when the door is in closed position, the hook 3 may be made to pass through the eye 6 whereby the door may be held fast.

In practice it has been found that the hook 3 is apt to escape from the eye 6 and permit opening of the door 1 when not desired, and by use of the present invention this accidental unfastening of the hook is avoided.

The invention employs a plate 7 prefer-

ably of the elongated rectangular construction shown, and provided with perforations to receive the upper screw 8 and the screw eye 6 whereby such plate 7 may be secured to the door 1. The plate carries a staple 9 in which the downwardly turned perforated ears 10 of a lever 11 are fulcrumed, and above the staple 9 the end of the lever is turned up as indicated at 12 to provide an operating piece adapted to be pressed down against the plate 7 whereby the opposite end of the lever 11 may be lifted away from the eye 6, as shown in dotted lines in Fig. 2.

The lever 11 is narrowed at its intermediate portion from which the ears 10 are stamped and bent over, and the same flares outwardly toward its lower end where it is centrally provided with a lug 13 which is bent upwardly and curved to conform substantially to the curvature of the rounded portion of the hook 3 which it engages as shown in Figs. 1 and 2, and in this manner serves to hold the hook 3 in the eye 6 and prevents its escaping therefrom.

Horns 14 and 15 are formed in one piece with the lever 11 and cut and twisted from the lower end thereof, such horns being disposed to opposite sides of the lug 13 and acting to center the lug on the hook and prevent any lateral escape of the hook from the eye 6. These horns 14 and 15 project forwardly and outwardly, as is clear from Figs. 1 and 3. The horns 14 and 15 are severed along their rear side from the adjacent portions of the lever 11, and such adjacent portions are bent down to provide prongs 16 of substantially triangular construction adapted to rest against the plate 7 when the lever 11 is in the locking position. The prongs 16 are shown engaging the plates 7 in Fig. 2, and they act to hold the lever away from the plate a suitable distance to permit the lug 13 and the horns 14 and 15 to have proper engagement with the hook 3.

In use, the parts are in the position shown in Figs. 1 and 2, in which case the hook 3 is effectually secured in place and its escape is provided against. However, when it is desired to open the door 1, the hook 3 may be released by first depressing the operating piece 12 which causes the rocking of the lever 11 from the full to the dotted line position shown in Fig. 2, and when in this condition the lug 13 and the horns 14 and 15 are lifted clear of the hook 3 to permit the latter to be lifted out of the eye 6. The

arrangement is such that the hook 3 may be engaged with and disengaged from the eye 6 by one hand while the operating piece 12 of the lever 11 is depressed by the other 5 hand, so that the unhooking of the door 1 may be readily accomplished.

It is obvious that those skilled in the art may vary the details of construction and arrangements of parts without departing from 10 the spirit of my invention, and therefore I do not wish to be limited to such features except as may be required by the claims.

I claim:

1. In combination with a hook and an 15 eye, a lever having a lug struck up from one end and arranged to engage the hook when the lever is in one position to prevent its escape from the eye, said lever also having horns formed on the end thereof and at op- 20 posite sides of said lug, prongs also formed on the end of said lever for holding the

lever with the lug engaged with the hook, and an operating piece on the other end of the lever whereby the lever may be rocked to withdraw the lug and horns from the 25 hook, substantially as described.

2. A device of the character described including a hook, an eye, a plate having a perforation adapted to receive said eye, the eye assisting to hold the plate in place, a lever 30 having perforated ears struck therefrom and fulcrumed on said plate, a turned up end on one end of the lever acting as an operating piece whereby the lever may be swung on said fulcrum, prongs bent from 35 the other end of the lever and adapted to engage said plate, horns adjacent said prongs, and a curved lug between said horns and adapted to engage the hook and hold the same in the eye, substantially as de- 40 scribed.

LEWIS PETER BOURGEOIS, JR.
